(57) **CLAIM**

The ornamental design for a gun grip as shown and described.

DESCRIPTION

FIG. 1 is a front elevational view of a gun grip showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof; and,

FIG. 8 is an enlarged view of portion 8 in FIG. 7.

The dash-dot broken lines in the drawings depict the extent of the enlarged view of the gun grip and form no part of the claim.

The broken lines in the drawings illustrate portions of the gun grip which form no part of the claimed design.
